UNITED STATES PATENT OFFICE

GUSTAVUS A. PFEIFFER, OF NEW YORK, N. Y.

FACE-POWDER BOX

Application filed December 27, 1928. Serial No. 328,709.

This invention relates to a face powder box and has for a special object to provide a face powder box having a cylindrical wall, and a cover for such box having an inner cylindrical surface corresponding to the outer face of said cylindrical wall and having an outer ornamental surface that need not conform in any way to the cylindrical wall of the box.

To this end, the present invention specifically aims to provide a face powder box having a cylindrical wall, and a cover composed of two shells, an inner shell having a cylindrical skirt that conforms with and is adapted snugly to receive the cylindrical wall of the powder box, and an outer shell having a skirt that is ornamentally formed to correspond to a polygon or any other figure that does not correspond to the cylindrical wall of the powder box, whereby advantage is taken of the fact that two cylindrical surfaces can be readily turned or twisted and that such torsional strain will serve quickly to break the surface adhesion between the two adjacent cylindrical walls, to wit, the co-action of the outer face of the cylindrical wall with the inner face of the cylindrical skirt of the inner shell, whereupon the cover can with facility be raised and removed from the box without requiring the application of any violent drawing forces to start the removal of the cover and the accompanying tendency to lose control of the box or unduly to agitate the contents of the box to cause the same to be spilled or sprayed about.

Among the objects of the present invention it is also aimed to provide a cover for a face powder box having an outer ornamental shell which may be composed of a delicate substance and an inner reinforcing shell for strengthening the outer shell.

It is still another object of the present invention to provide an improved cover, the inner box fitting wall of which is formed into a shape that can be readily fitted with accuracy to protect the contents of the box from leakage and that can readily be produced into a neat and workmanship product without undue care and skill while the outer ornamental portion of the cover might assume most any

conformation entirely disregardful of the conformation of the lateral wall of the box.

These and other features, capabilities and advantages of the invention will appear from the subjoined detail description of one specific embodiment thereof illustrated in the accompanying drawings, in which

Figure 1 is a plan of the face powder box with the cover in closed position;

Fig. 2 is a side elevation of the same with the cover in section;

Fig. 3 is a side elevation with the cover partly raised; and

Fig. 4 is a plan looking upwardly at the cover when removed from the box.

In the embodiment illustrated, the face powder box B is shown provided with a base 1, and a cylindrical lateral wall 2 extending upwardly therefrom.

The cover C consists essentially of two shells, an inner shell 3 and an outer shell 4. The inner shell 3 consists of a disk portion 5 and a cylindrical skirt 6 extending therefrom. The outer shell 4 consists of a disk portion 7 and an ornamental skirt 8, in the present instance polygonal, or rather octagonal in outline, which skirts preferably extend down to the base 1 when the cover C is in closed position. The inner shell 3 is contained in the outer shell 4 and has outer face portions of its skirt 6 secured to inner face portions of the skirt 8. Between the disk portions 5 and 7 of the shells 3 and 4 respectively, there is formed a spacing member 9 to which the respective disk portions are preferably secured. Such spacing member serves to give the outer face of the disk portion 7 of the cover C a cushion-like outer appearance.

In the production of the box and cover as aforesaid, so far as fitting is concerned, it is only necessary to form the skirt 6, and of it, only its inner cylindrical face to conform to the outer cylindrical face of the lateral wall 2 of the box B, a rather simple operation, as distinguished from fitting two registering polygonal faces. As an instance, if the lateral wall of the box were octagonal, to fit a cover to such octagonal lateral wall and protect the same against leakage and at the same

time produce a neat and workmanship article, care must be exercised not only that the several angles and faces of the outer face of the lateral wall of the box correspond with one another but also that the several angles and faces of the inner face of the inner skirt correspond with one another, and in addition thereto, with the angles and faces of the lateral wall of the box, since the same faces of 10 the inner skirt of the cover will not always oppose the same faces of the lateral wall of the box during the use of the article.

When the opposing faces are cylindrical, little if any care need be exercised since only 15 one face need be fitted and paper is of course sufficiently flexible to compensate for any slight irregularities that might occur between the two opposing cylindrical faces.

Aside from the foregoing, advantage is 20 here taken of the fact that two opposing cylindrical faces may be readily twisted or turned relative to one another to overcome any adhesion that might exist between the opposing faces, and to overcome the resistance offered 25 by the tendency to form a vacuum between the inner face of the disk 5 of the cover C and the upper face of the seal 10 or the upper surface of the powder in the box B. When the seal 10 has been destroyed and the box is 30 in use, the reduction in pressure between the inner face of the disk 5 and the upper surface 95 of the powder in the box B would, of course, tend to agitate the powder and cause it to spray and spill as soon as the cover came off, 35 a not unusual occurrence today. In addition to the foregoing, due to the adhesion of the opposing faces and the reduction in pressure within the box when drawing the cover from the box, the tendency of the user when not careful is to apply a sudden violent drawing 40 force resulting in the powder spilling upon the sudden interruption to the resisting force 100 at the moment when the cover is removed.

It is obvious that various changes and modifications may be made to the details of construction without departing from the general spirit of the invention as set forth in the appended claims.

I claim:

50 1. The combination with a face powder box 115 having a cylindrical lateral wall, of a cover having an inner shell and an outer shell secured to one another, said inner shell having a cylindrical skirt conforming to, and fitting, 55 said cylindrical lateral wall, and said outer shell having a skirt polygonal in outline.

2. The combination with a face powder box having a base and a cylindrical lateral wall extending therefrom to form the box, 60 of a cover having an inner shell and an outer shell secured to one another and extending down to said base in closed position, said inner shell having a disk and a cylindrical skirt 65 extending from said disk and conforming to, and fitting, said cylindrical lateral wall, and

70 said outer shell having a disk secured to the disk of said inner shell and having a skirt polygonal in outline and extending adjacent to, and being secured to, the skirt of said inner shell.

3. The combination with a face powder box 75 having a base and a cylindrical lateral wall extending therefrom, of a cover having an inner shell and an outer shell, said inner shell having a disk and a cylindrical skirt extending from said disk and conforming to, and fitting, said cylindrical lateral wall, said outer shell having a disk and a polygonal skirt 80 extending from said latter disk, and a spacing member disposed between the disks of said shells to form a cushion effect on the disk of said outer shell, the skirts of said shells being secured to one another.
